AIRCRAFT BACK-TURRET CUPOLA

Ettore Lanciani, Milan, Italy; vested in the Alien
Property CustodianApplication September 20, 1940, Serial No. 357,514
In Italy September 25, 1939

3 Claims. (Cl. 89—36)

This invention is a novel aircraft back turret cupola, in the nature of a top enclosure or hood placed protectively above the rear gun turret of any type of aircraft, the combined turret and hood being adapted to enclose a machine gun or other firearm, as well as the gunner or operator thereof. The novel features of the invention may be disclosed without the need of illustrating the aircraft, or fuselage; and for that matter the gun turret itself need not be disclosed, except by reference to an illustrative gun turret adequately shown in this applicant's copending application filed December 16, 1939, Serial No. 309,569 directed to Armed rotating turrets for aircraft, Fig. 1 of which in particular well shows such a gun turret, and machine gun, with a general indication of a covering hood or cupola protectively extending above the space accommodating the gun and gunner; the turret illustrated in the copending application being of the revolvable type so that, notwithstanding that the turret may be located near the rear of the aircraft, the gun may be swung leftward or rightward to a certain extent in aiming or following the target, while naturally the gun and mechanism also are trunnioned for upward and downward swing to adjust the firing elevation.

The general object of the present invention is to afford, especially for the rear gun turret for aircraft, a construction or physical shaping such as to afford important operational advantages. One such advantage is to afford superior visibility for the gunner. Another advantage relates to the matter of the relative wind, or rearward air flow about the aircraft, and has to do with the minimizing of the resistance of the turret and cupola to the wind, and the minimizing of eddies near the rear or tail side of the combined turret and cupola. Other advantages will appear from the hereinafter following description of an illustrative example of the invention.

In the accompanying drawing, Fig. 1 is a top plan view of a turret cupola or hood adapted to serve as a top covering for a revolvable gun turret such as shown in said application No. 309,569; this figure containing the direction arrow T to indicate the forward direction of travel of the aircraft, and the firing arrow F of the gun G, showing that it is mounted in a rear turret for firing oppositely to the direction of travel.

Throughout this description the line of direction of the arrows T and F, as shown, will be considered as the longitudinal direction, although naturally the turret may be swung

through an extent of arc, to either side of the longitudinal, by the rotation of the turret and covering cupola. The circular shape of the cupola indicates its rotatable character, about 5 the vertical axis V of the turret.

Fig. 2 is a longitudinal section view taken on the section line 2—2 of Fig. 1, slightly on the near side of the longitudinal diameter.

Fig. 3 is a similar longitudinal section, taken 10 on the line 3—3 of Fig. 1, subtending a somewhat shorter chord.

Fig. 4 is a transverse sectional view taken on the section line 4—4 of Fig. 1, certain parts to 15 the right thereof being seen in interior view.

Fig. 5 is a section taken on a shorter chord, 20 namely on the section line 5—5 of Fig. 1.

The cupola or hood thus illustrated may be 25 considered as adapted to be set down in covering position upon a rotatable or oscillating cupola such as that illustrated in said application No. 309,569, with a sufficient arching or crowning of the covering cupola to accommodate the machine gun, directed rearwardly, and the gunner facing rearwardly, usually with the gun at his 30 righthand side, and the ammunition feeding mechanism at the other side of the gun. The mode of mounting the cupola upon the turret, and its attachment there, are deemed unnecessary to indicate since the present invention is concerned not with such details but with the structure and shape of the cupola itself, as will next be described.

The cupola is seen to comprise a walled structure, the general portion 7 of which is of generally round outline and thus adapted to be placed upon the turret to cover the enclosed gun and gunner, and such general wall of the cupola being of generally arched, cambered or crowned shape, with its longitudinal sections

40 generally of substantially airfoil or streamline contour. For illustration, two such longitudinal sections have been illustrated in Figs. 2 and 3 where it will be seen that, except for a minor interruption to be described, the cambered shape 45 is of airfoil or streamline contour, comprising at its front portion or end an enlarged bulbous shape 8, passing around to a peak somewhat forward of the center, and thence with tapering away shape 9 toward the rear or tail end of the section.

With the same exception, the transverse sections 50 are of generally convexly arched curvature, and preferably substantially symmetrical, as best shown in the diametral section view Fig. 4. The curvature of the transverse section shapes 55 is shown as involving a convenient polycentric

curvature, with of course the convexity above.

By this improvement as thus far described, a revoluble rear gun turret cupola is provided which minimizes relative wind resistance and at the same time greatly reduces eddying of air around the rear portion of the circular contour.

A cooperating feature of improvement may be described as follows. The cupola, at one side of its rear portion, preferably within a quadrant as shown, is shaped into a reentrant recess or depression, which breaks into but merges with the arched general curvature of the cupola, and such depression comprising a steeply inclined wall or shield affording effective rear vision, this wall being transparent or windowed. This special structure is well illustrated in all of the figures of the drawing, the sunk wall portion or depression comprising, in the illustrated case, a substantially flat or horizontal wall part 10, from the front edge of which extends a slanting wall 11, the upper edge of which is connected or integral with the general arched wall 7 of the cupola. As best shown in Fig. 3 the wall part 11 is steeply inclined, being shown at about 45°; and it is in the nature of a windshield, either wholly transparent, or having a window 13 through which the gunner is afforded a clear rearward view for aiming and firing purposes.

In addition to the flat wall 10, and the inclined wall 11, the recessed shape of the cupola is bounded by a triangular upstanding wall 14, see more especially Figs. 2 and 5, the top of which connects or merges with the general wall portion 7, and the other edges of which are united with the wall portions 10 and 11 respectively. By this shaping the entire interior is enclosed and protected from exposure and weather. The three walls 10, 11 and 14 are preferably plane.

The following general arrangement is preferred. The gunner sits behind the vision wall 11, looking rearwardly, at the left part of the enclosed space, while the gun preferably is located to the right of the upright wall 14, and therefore within the opposite side of the turret space. The gun G naturally must protrude from the cupola, as in said copending application, and for this purpose the general wall or shell portion

7 of the cupola is cut away to form an aperture 12, in the nature of an elongated slot permitting up-and-down swinging of the gun in training it upon the target.

While the described depression parts of the cupola wall, which may be struck from the general material, constitute somewhat of an interruption, at one rear quadrant of the streamline contour, the loss of airfoil effect is minimized by the fact that the wall 11 slants downwardly and rearwardly, and to some extent preserves the desired contour to minimize air resistance and eddying, as is clearly seen by comparison of Figs. 2 and 3.

Naturally the exact constructional shape and details may be considerably varied without departing from the principles described, and it is not intended to limit the invention to the illustrative disclosure of the drawing.

What is claimed is:

1. A cupola for an aircraft rear gun turret, comprising a walled structure having a generally circular outline adapted to be placed over the turret to cover the gun and the gunner, said cupola structure being characterized in having its wall of generally cambered shape and wherein the wall at one side of its rear portion is shaped into a reentrant depression breaking but merging with the arched general curvature of the cupola, such depression comprising a base and a steeply inclined wall or shield affording effective clear vision, the sections of the cupola in direction of travel of the aircraft, except at said depression, being of air foil contour and its sections transverse thereto except at said depression being convexly arched.

2. The structure set forth in claim 1 wherein the depression occupies approximately one rear quadrant of the cupola and wherein an opening is provided in the adjacent rear quadrant through which a gun may be fired.

3. The structure set forth in claim 1 wherein the base of the depression is substantially flat and in the plane of the air foil tip and the inclined wall makes an angle with the extension of such plane of approximately 45°.
